United States Patent

Des. 238,810
Patented Feb. 10, 1976

238,810

PENDANT OR SIMILAR ARTICLE

Margareta C. Roberts, Providence, R.I., assignor to Reed and Barton Corporation, Taunton, Mass.

Filed May 28, 1974, Ser. No. 474,876

Term of patent 14 years

Int. Cl. D11—01

U.S. Cl. D45—17

FIG. 1

FIG. 2

FIG. 3

FIG. 4

FIG. 5

FIG. 1 is a front elevational view of a pendant or similar article showing my new design;

FIG. 2 is a rear elevational view thereof;

FIG. 3 is a right side elevational view thereof;

FIG. 4 is a top plan view thereof; and

FIG. 5 is a bottom plan view thereof.

I claim:

The ornamental design for a pendant or similar article, substantially as shown.
